DESIGN FOR A BLOTTER UNIT

Martin E. Trolle, St. Paul, Minn., assignor to
Brown & Bigelow, St. Paul, Minn., a corpora-
tion of Minnesota

Application February 7, 1940, Serial No. 90,087

Term of patent 14 years

To all whom it may concern:

Be it known that I, Martin E. Trolle, a citizen of the United States, residing at St. Paul, county of Ramsey, and State of Minnesota, have invented a new, original and ornamental Design for a Blotter Unit, of which the following is a specification, reference being had to the accompanying drawing, forming part thereof:

Figure 1 is a front elevational view of a blotter unit showing my new design.

Figure 2 is a rear elevational view.

Figure 3 is a top plan view.

Figure 4 is an end elevational view.

My design for a blotter unit is characterized by the specific configuration of the clip member and its placement on the design.

I claim:

The ornamental design for a blotter unit, as shown and described.

MARTIN E. TROLLEN.
